UNITED STATES PATENT OFFICE.

GEORGE A. ROBERTSHAW, OF GREENSBURG, PENNSYLVANIA.

VALVE.

Application filed August 21, 1924. Serial No. 733,423.

The present invention relates broadly to flow control valves, and more particularly to thermostatic valves of the character particularly adapted for use in controlling the flow of gaseous fuels to a burner.

At the present time, it is customary in the art to which this invention relates, and more particularly in connection with household installations of the character ordinarily referred to as storage water heaters, to provide a main burner and a pilot, the main burner being thermostatically controlled to permit the maintenance of a predetermined temperature within the storage tank at all times, and the pilot being designed to serve as a relighting means for the fuel when the main valve is again opened by the thermostat.

In accordance with the usual practice, such pilot flames have been controlled by a by-pass which has been manually adjusted. The adjustment of such by-passes depends upon the quality of the gas, the pressure at the time of adjustment and the size of pilot flame necessary to prevent quenching when the main gas supply is turned on, or when the quality of the gas varies or the pressure drops after the by-pass has been set. If the burner is of the type that will flash back in the mixer on low consumption, the burner may continue to burn in the mixer and deposit carbon on the heating sections or coils. Such an adjustment is objectionable not only from the fact that the quality and pressure of the gas may vary, but also for the reason that frequently an unnecessarily large pilot flame is utilized in order to insure proper operation, thereby resulting in an unnecessarily large fuel bill. Furthermore, such adjustments must frequently be made by persons more or less unskilled in the operation of thermostats, and the burning of fuel, thereby often resulting in unsatisfactory operation.

The present invention has for one of its objects the provision of a by-pass which requires no manual adjustment and which is automatically operable independently of the efficiency of the system in connection with which it is used and irrespective of the quality or pressure of the fuel being burned.

In the accompanying drawings, there are shown for purposes of illustration only certain preferred embodiments of the present invention, it being understood that changes may be made in the details of construction

and operation without departing from the spirit of the invention as defined in the appended claims.

In the drawings:

Figure 1 is a longitudinal sectional view through one form of thermostat constructed in accordance with the present invention;

Figure 2 is a detail sectional view on an enlarged scale of the controlling apparatus;

Figure 3 is a view similar to Figure 2, illustrating a slightly modified embodiment of the invention; and

Figure 4 is a graphic view illustrating the operation of the valve for one temperature setting.

In carrying out the present invention, there may be provided a valve casing 2, having a suitable inlet connection 3 and an outlet connection 4, the flow between these connections being controlled by a valve 5, 75 cooperating with a seat 6. This valve is illustrated as being of the character normally urged in one direction by a spring 7 and in the opposite direction by thermostatic means 8. In the form of invention illustrated, the 80 thermostatic means is effective for opening the valve 5 against the action of the spring 7.

The operating connection between the thermostatic means and the valve may comprise a packing pin 9, slidably mounted 85 within a bearing 10 and abutting at one end against a projection 11 on the valve, which projection is also journaled within the bearing 10. At its opposite end, the packing pin may engage an adjustment 12, whereby the 90 temperature at which the thermostatic means is effective for opening the valve may be varied at will.

In order to provide a by-pass between the inlet and the outlet, there is shown a by-pass valve 13, carried by the valve 5 and cooperating with a seat 14 within a projection 15 thereon, the valves preferably being arranged in concentric relationship. The by-pass valve is normally urged in one direction by a spring 16, this spring here being shown as effective for tending to move the valve toward closed position, and is operated in the opposite direction by a stem 17, extending through the projection 11 on the valve 100.

5. The stem 17 is preferably of such length that with the valve 13 against the seat 14, it will extend slightly beyond the end of the projection 11 and into engagement with the packing pin 9. The exact amount which the 110

stem 17 projects may be varied in accordance with the operating conditions desired. I have found that with a thermostatic means utilizing a carbon rod as the non-expansible element, the amount of projection may be .0015 of an inch, where it is desired that there should be a difference of between 20 and 30° F. between the closing of the main valve 5 and the closing of the by-pass. The 10 main valve is illustrated as provided with an opening 18, permitting the passage of gas therethrough when the by-pass valve is in spaced relation to its seat.

In operation, it may be assumed that the 15 thermostat is threaded into a hot water storage tank, a portion of which is indicated at 19, and that the water therein is below the desired temperature. At this time, the thermostatic means 8 will act through the stem 17 and the projection 11 to maintain both of the valves in open position, thereby permitting a full flow of gas from the inlet to the outlet. If the adjustment 12 is set at such position that a temperature of substantially 25 135° F. to 140° F. will be maintained within the storage tank, the thermostatic means will permit the closing of the valve 5 when this temperature has been reached. Due to the projection of the stem 17, however, 30 this thermostatic means will be effective after the closing of the valve 5 for maintaining the by-pass valve in open position. Consequently, the temperature of the water will have to be raised an amount corresponding 35 to that required to cause expansion of the thermostatic means sufficient to entirely release the stem 17 before the by-pass valve will be closed. However, after the valve 5 is closed, considerable time will elapse before 40 the temperature of the water can be raised 20° or even less by means of the small gas flow through the by-pass valve 13. Accordingly the water within the tank 19 will, by convection, reach a substantially uniform 45 temperature at all levels and the by-pass valve will supply approximately sufficient fuel to offset radiation in the tank. As the 50 temperature of the water drops, due to demand on the tank, the by-pass valve will be fully opened before any opening of the main valve, thereby insuring a pilot flame of sufficient size to overcome any possibility of 55 quenching under the influence of the full gas flow.

Where heaters are of known efficiency and of known construction, there may be utilized a by-pass valve of the character shown in Figure 3 of the drawings, in which the by-pass valve 13' is formed with a calibrated 60 opening 20 of a size calculated to pass the minimum amount of pilot gas under most favorable conditions. In such a construction, the valve 13' will be operative for increasing the gas flow from this minimum 65 amount up automatically as needed to offset

radiation. Such a calibrated opening may be used either with or without an adjustable by-pass of the character shown in Patent No. 864,263, to F. W. Robertshaw, dated Aug. 27, 1907. Such a by-pass may also be used 70 with the form of the invention illustrated in Figures 1 and 2.

In Figure 4 of the drawings there is a graphic illustration showing more clearly the operation of a valve constructed in accordance with the present invention. In this figure, the ordinates represent the number of cubic feet per hour at an arbitrary pressure, the curve illustrated in this figure being plotted with the use of gas under a 6 inch pressure. The abscissas represent degrees Fahrenheit of the liquid or other substance being controlled. The valve was set to cut off the flow of gas at between 135° and 140° F. With a temperature of 110° it will be noted 80 that there was a gas flow at the rate of approximately 32 feet per hour. At 120° there was a gas flow at the rate of 24 feet per hour, while at a temperature of 130° the gas had dropped to 8 cubic feet per hour. At this 90 point, indicated on the curve as A, the main thermostatic valve 5 commenced to close very quickly, the completion of the closing movement of the main valve occurring at the point B corresponding with a temperature 95 of 140° and a gas flow at the rate of 4 feet per hour. Thereafter, the rate at which the gas flow was cut off decreased very perceptibly, the rate of flow only changing from 4 feet per hour to slightly less than 2 feet per hour for a temperature variation of 30° F. It will be apparent from this curve that the present invention provides means for thermostatically throttling a fuel supply at different rates of rapidity, there being one rate 100 substantially constant up to the point A, another rate from A to B, and a third rate after the closing of the main valve. It was found that these general conditions were not affected by a change in the temperature adjustment or setting of the thermostat. Irrespective of the point at which the thermostat was set to cut off the main fuel flow, there would still be produced a fuel 105 throttling at different rates of rapidity. This establishes a ratio of throttling speed differential, the by-pass controlled by the thermostat constituting means for maintaining a substantially definite ratio, as before 115 referred to.

Because of this slow closing at the low point only of the curve, it is possible to obtain the advantage of an increased capacity at lower temperatures when much gas is needed, and thereafter the benefit of a slow-working small valve which is not seriously influenced by sudden temperatures of a few degrees either up or down. As before pointed out, by reason of this operation, in many 125 appliances of definitely established efficiency 130

the thermostat will settle and automatically adjust its own carrying point.

Certain advantages of the present invention arise from the provision of an automatically operated by-pass requiring no manual regulation or adjustment and operable to insure the desired gas flow independently of gas quality, gas pressure or efficiency of the burner installation with which it is used.

Further advantages of the present invention arise from the provision of a fuel valve of the character referred to operable for throttling a fuel supply at different rates of rapidity, the rates not being changed by temperature adjustment or setting, together with means for maintaining a definite ratio of throttling speed differential.

I claim:

- 20 1. In a flow control, a main controlling valve, a temperature controlled by-pass valve cooperating therewith, and a temperature responsive means axially aligned with said valves and structurally disconnected from both of said valves said means being adapted to successively engage with and become disengaged from said valves for controlling the operation thereof, substantially as described.
- 25 2. In a flow control, a main valve, a by-pass valve, and temperature responsive means axially aligned with said valves and having an abutting contact only with said valves for operating the same simultaneously at certain periods and successively at other periods, substantially as described.
- 30 3. In a flow control, a main controlling valve having a guided stem, a by-pass valve having a guiding stem extending through and projecting beyond the guided stem on the main valve, and operating means cooperating with said stems for initially opening the by-pass valve, and thereafter opening the main valve, substantially as described.
- 35 4. In a flow control, a main controlling valve, a by-pass valve having a seat in said main controlling valve, and thermostatic means for operating both of said valves, substantially as described.
- 40 5. In a flow control, a valve casing having inlet and outlet ports, a main controlling valve therein controlling the flow between said ports, said valve being provided with a bypass port leading from one side to the other thereof, a bypass valve carried and guided by said main controlling valve and controlling the flow through said bypass port, and thermostatic means for operating both of said valves, substantially as described.
- 45 6. In a flow control, a valve casing, a main controlling valve having a by-pass opening through the body of the valve itself, a by-pass valve controlling said opening, and thermostatic means for initially opening said by-pass valve and thereafter opening said

main controlling valve, substantially as described.

7. A thermostatic valve comprising a valve casing, a main controlling valve therein, means for guiding said valve, said valve having a by-pass opening therethrough, a by-pass valve controlling the flow through said opening and having an operating stem projecting therefrom, and thermostatic means adapted to initially engage said stem to open the by-pass valve and thereafter engage the main controlling valve for opening the same as required, substantially as described.

8. A thermostatic valve comprising a main controlling valve and a thermostatically controlled by-pass therethrough, substantially as described.

9. A thermostatic valve comprising a main controlling valve and a thermostatically controlled by-pass valve concentrically carried by said main valve and having a seat therein, substantially as described.

10. In a fuel control, a compound valve structure comprising a valve casing having a seat, independently movable valves in said casing, one of said valves cooperating with said seat and providing a seat for another valve, and thermostatic means operable throughout one temperature range for throttling the fuel supply relatively quickly, and throughout a succeeding temperature range to throttle the fuel supply relatively slowly, substantially as described.

11. In a fuel control, a compound valve structure comprising a valve casing having a seat, independently movable valves in said casing, one of said valves cooperating with said seat and providing a seat for another valve, thermostatic means operable throughout one temperature range for throttling the fuel supply relatively quickly, and throughout a succeeding temperature range to throttle the fuel supply relatively slowly, and means for adjustably varying said first mentioned temperature range, substantially as described.

12. In a flow control, a main controlling valve having a valve stem, a by-pass valve having a valve stem, and common means having abutting engagement only with said valves by direct engagement with said stems for operating such valves simultaneously at certain periods and successively at other periods in both directions, substantially as described.

13. In a flow control, a main controlling valve having a valve stem, a by-pass valve having a valve stem, and common means having abutting engagement only with said valves by direct engagement with said stems for initially opening the by-pass valve and thereafter opening the main valve, substantially as described.

In testimony whereof I have hereunto set my hand.

GEORGE A. ROBERTSHAW.
